VEGETABLE SLICER

Paul R. McVicker, Royal Oak, Mich., assignor of one-half to Emmett J. Carroll, Detroit, Mich.

Application December 22, 1947, Serial No. 143,288

Term of patent 7 years

(Cl. D89—1)

To all whom it may concern:

Be it known that I, Paul R. McVicker, a citizen of the United States, residing at Royal Oak, in the county of Oakland and State of Michigan, have invented a new, original, and ornamental Design for a Vegetable Slicer, of which the following is a specification, reference being had to the accompanying drawing, forming part thereof.

Fig. 1 is a perspective view of a vegetable slicer, showing my new design.

Fig. 2 is a perspective view of the slicer taken from the left of Fig. 1, part of the side wall being removed for convenience of illustration.

I claim:

The ornamental design for a vegetable slicer, as shown and described.

PAUL R. McVICKER.
